US00D351414S

United States Patent [19]Bühner[11] Patent Number: Des. 351,414[45] Date of Patent:  Oct. 11, 1994[54] THIRTEEN-MONTH CALENDAR

[76] Inventor: Manfred Bühner, Hochholzweg 26,
D-7000 Stuttgart 75, Fed. Rep. of Germany

[] Term: 14 Years

[21] Appl. No.: 2,047

[22] Filed: Nov. 30, 1992

[30] Foreign Application Priority Data

May 30, 1992 [DE] Fed. Rep. of Germany 9204070

[52] U.S. Cl. D19/20

[58] Field of Search 40/107-122;

282/2; 434/150; D19/20, 21, 22, 23, 24, 25, 59,
26

CLAIM

The ornamental design for a thirteen-month calendar, as shown and described.

DESCRIPTION

The FIGURE is of conventional thickness and the undisclosed rear is flat and plain.

The stippled shading in the boxes indicates a color contrast.
